UNITED STATES PATENT OFFICE

2,021,392

ELECTRIC ELEVATOR SAFETY DEVICE

Philip D. Tardiff, Detroit, Mich.

Application May 2, 1932, Serial No. 608,669

3 Claims. (Cl. 187—31)

My invention relates to a new and useful improvement in electric elevator automatic safety relays, and is in part an improvement on Patent No. 1,805,196 issued to me on May 12, 1931. All 5 of the advantages sought and obtained by the construction illustrated in the patent referred to are obtained in the present invention. The additional feature, however, is provided in this invention in that, should the gate switch or switches 10 not close when the gate or gates open to a predetermined distance, an auxiliary or secondary switch will be opened which will break the circuit to the coil which holds the breaker in, and thus the breaker will be drawn out and the power to the line shut off so that the power to 15 the elevator controls will be shut off. The object of the invention therefore is to render the operation of electrically operated elevators more safe than even where the invention set forth in the patent referred to is used.

Another object of the invention is the provision in a safety device of this class of a plurality of relays interlocked so that the failing of one of the relays to function will so effect the other relays that the safety factor of the non-functioning relay will be supplied by the effect which the non-functioning thereof will have on the other relays interlocked in the set.

Another object of the present invention is the provision in a safety device of this class of a plurality of automatically operated relays so connected that a slight defectiveness in the operation or function of one will affect the complete functioning of others.

Other objects will appear hereinafter.

The invention consists in the combination and arrangement of parts hereinafter described and claimed.

The invention will be best understood by a reference to the accompanying drawings which form a part of this specification, and in which,

Fig. 1 is a diagrammatic view illustrating the wiring used in the invention and illustrating in diagrammatic form the operating levers.

Fig. 1a is a diagrammatic view illustrating the wiring to which the mechanism is connected.

The invention may be used with elevators having gates. I provide a construction embodying an operating arm 7 which is reciprocated upon the opening and closing of the elevator gate. Pivotedly connected to the arm 7 are the links 8 and 9. The link 8 is pivotally connected to the stud or shaft 10, and the link 9 is similarly connected at one end to the stud or shaft 11. The upper ends of the studs 10 and 11 are formed with

flat faces 12 over which engages one end of a clip 15 which has an opening formed therein with flat faces to engage the flat faces 12. A bolt 12' is threaded into each of the studs 10 and 11 to hold the clips 15 in position. Each of the arms 8 and 9 is provided with an arcuate transversally extending slot 13. Projected through the slot 13 and through the free end of the clip 15 is a bolt 14 having a nut threaded thereon and so arranged as to clamp this end of the clip 15 in fixed relation to the arm 8 or 9 as the case may be. When the clip 15 is clipped in fixed relation to the arm 8 or 9, a rocking of the arm 8 or 9 will effect a rotation of the shaft or stud 10 or 11. The slot 13 is provided so that the 20 relative position of the stud 10 or 11 to its arm 8 or 9 may be determined and thus the switch mechanism which is operated by these studs adjusted to the desired position of operation so that these switches will open and close at predetermined positions of the arms 8 and 9.

Fixedly mounted on the stud 10 is a block 16 formed from insulating material and carrying the outwardly projecting contacts 17 and 18 which are positioned at diametrically opposite 25 sides of the block 16 and which are electrically connected to each other by the metallic ring 18' which is integral with contacts 17 and 18 and which is imbedded in the insulating block 16. Fixedly mounted on the stud 11 is a similar block 30 19 of insulating material which carries the outwardly projecting contacts 20 and 21 positioned at diametrically opposite points on the block 19 and connected to each other in a similar manner.

When the shaft 10 is rotated to a predetermined position the contacts 17 and 18 will engage the contact arms 22 and 23 and thus close the circuit between these arms. The arms are mounted on a suitable support and springs 24 and 25 serve to normally prevent a separation or spreading of these arms. A casing 25' serves to enclose the arms 22 and 23 as well as the supports 114 on which these arms are mounted, these arms being spaced apart by the spacing block 116 formed from insulating material. Arms 27 and 28 are mounted similarly to the arms 22 and 23 on suitable supports 115 in a housing 25'. These arms are similarly spaced by a spacing block 116. When the shaft 11 is rotated to a predetermined position, the contacts 20 and 21 will engage the contact arms 27 and 28 and close the circuit between these arms, and when the member 19 is turned to another position, the arms 27 and 28 will disengage from the contacts 21 and 20 and be spread apart by the member 19, the spreading 55

apart of which is resisted by the springs 29 and 30. The contact arm 22 is connected to the wire 31 which is connected through the fuse 32 to the negative feed line. The contact arm 23 is connected by the wire 33 through the junction box 42 to the contact 34. This contact 34 is connected through the resistance coil 35 to the contact 36. The contact 36 is connected by the wire 37 to the coil 38. This coil 38 may be termed the first gate relay switch. The coil 38 connects through the fuse 39 to the positive feed line 40. The wire 41 also connects the wire 40 through the junction box 42 with the contact arm 28. The portions of the wires between the junction box 42 and the contact arms 22 and 23, 27 and 28 constitute the traveling cables on the elevator. The core 44 of the coil 38 is provided with cross heads or contact arms 45, 46, 47, 48, and 49. The cross head or contact arm 45 is adapted to engage and close the circuit between the contacts 50 and 51. The contact 51 is connected through the resistance 52 and the wire 52' to the positive feed line of the brake coil 386. The contact 53 is connected by the wire 53 to the coil 54 which is connected by the wire 55 to the negative side of the brake coil 386, shown in Fig. 1a. The contact arm or cross head 46 is adapted to engage and close the circuit between the contacts 56 and 57. The contact 56 is connected by the wire 56' to the armature or motor 387 which is used for operating the elevators and the contact 57 is connected by the wire 58 to the contact 59. The cross head or contact arm 47 of the first relay switch 38 engages its contacts 60 and 62 to complete a holding circuit around the gate operated switches 27 and 28 for the second gate relay 78 (later to again be referred to) which circuit extends from a junction with conductor 41 by means of wire 61, through these said contacts 60 and 62 and contactor 47 to a junction point with conductor 63.

This conductor 63 is connected through the reset switch 64 and the wire 65 to the contact 66. The cross head 49 serves to connect electrically the contacts 34 and 36. The wire 63 is connected by the wire 68 to the contact 69 positioned opposite a contact 70 which is connected by the wire 71 to the contact 67. This contact 70 is also connected by the wire 72 to the contact 73 which is connected through the resistance 74 to the contact 75. This contact 75 is connected by the wire 76 to the wire 77 which is connected to the coil 78. This may be termed the second relay switch and is used to hold the breaker in. The core 79 of the coil 78 carries the cross heads 80, 81, 82, 83, and 84. The coil 78 is connected by the wire 85 to the contact 86. The cross head 80 serves to close the circuit between the contacts 87 and 88. These contacts 87 and 88 are interposed in the wire 113 which is the positive feed to the circuit breaker switch 388 of the elevator so that when the cross head 89 disengages from these contacts 87 and 88, the circuit to the elevator breaker coil 386 is broken. The cross head 81 serves to electrically connect the contacts 59 and 89. The contact 89 is connected by the wire 90 to the coil 91. This coil may be termed the third relay switch and is parallel with the armature. The coil 91 is connected by the wire 92 to the armature feed. The core 93 of the coil 91 carries the cross heads 94 and 95. The cross head 95 is adapted to close the circuit between the contacts 97 and 98, the contact 97 being connected by the wire 96 to the contact 114. The contact 98 is connected by the wire 99 to the con-

tact 101. The cross head 94 is adapted to engage and electrically connect the contacts 86 and 102. The contact 102 is electrically connected to the contact 103. The coil 54 which may be termed the fourth relay switch is provided with a core 104 carrying the cross heads or contact arms 105 and 106. The cross head 105 is adapted to electrically connect the contacts 103 and 107. The contact 107 is connected by the wire 109 through the fuse 32 to the negative feed line 32'. The cross head 106 is adapted to engage and electrically connect the contacts 101 and 115, a wire 110 connecting to the contact 115.

The cross head 81 serves to engage and electrically connect the contacts 89 and 59. The cross head 82 connects the contacts 114 and 111. The cross head 83 engages and electrically connects the contacts 69 and 70, while the cross head 84 engages and electrically connects the contacts 73 and 75. The wire 110 leads to the elevator control knife switch 389 which is mounted on the elevator board and the wire 112 connects to the circuit breaker coil 386 so that the contacts between the wire 110 and the wire 112 may be said to be interposed in the negative side of the circuit breaker coil 386 which is also the negative line of the elevator control and a safety switch. A consideration of Fig. 1a will indicate the various connections which are made to the control devices of the mechanism. At 390 I have illustrated a switch representing one side of the circuit breaker switch and at 391 is illustrated one of the elevator gate relay operated switches. At 392 I have indicated a starting switch which is mounted in the elevator car which connects through the wire 393 through the safety switch 394 which is also in the elevator car. The wires 395 and 396 pass through the control switches of the elevator to connect to the wires 397 and 398 respectively. The wire 397 connects through the 40 direction switches 399 and 400 to the wires 401 and 402 which form the field on the brake switch. The switch 399 may be considered the direction switch for controlling downward movement of the car and the switch 400 may be considered to control the upward movement of the car. The wire 398 leads to the upward direction switch 400' adapted to connect with the wire 402 and the wire 393 also leads to the downward direction switch 399' connecting to the wire 401. These switches are all located on the board. These switches 399' and 400' may also be termed the "field or brake switches". A direction switch 403 may also be termed a "field or brake switch" as may likewise the direction switch 404.

The wiring shown in Fig. 1a is a continuation of the wiring shown in Fig. 1. The wire 32' is a continuation of the wire 31 beyond the fuse 32 as shown in Fig. 1. The wires 110, 112, 113, 56' and 52' are all continuances of the wires shown in Fig. 1 as are likewise the wires 40, 92, 55 and 52.

In operation, when the gates are closed, the contact arms 27 and 28 will be in engagement with the contacts 21 and 20 so that they will be electrically connected. The contact arms 22 and 23 will be in engagement with the member 16 and spread apart. As the gates are opened, a rocking of the members 16 and 19 will be effected, the arm 7 being reciprocated upon opening and closing of the gates. When the gate has opened sufficiently so that the contacts 17 and 18 engage the arms 22 and 23, a circuit will thus be made through the arms 22 and 23. As an opening of the gate continues, the contact arms 27 and 28 will disengage from the contacts 20 and 21. This 75

disengagement, however, is subsequent to the making of a circuit through the arms 22 and 23. Should the device be defective for any reason so that when the arms 22 and 23 engage the contacts 17 and 18, the circuit would not be made, a further opening of the gates will break the circuit through the contacts 27 and 28, and this is a very important feature of the present invention, as it lends a safety factor to the entire structure and provides for an emergency which might arise through not making the circuit through the contact arms 22 and 23. The effect of the breaking through the contact arms 27 and 28 while the circuit through the contact arms 22 and 23 is open will be better understood by following the operation of the various switches and tracing the various circuits in the mechanism.

In the first gate relay switch, the circuit is as follows: the circuit beginning with the positive feed wire 49 passes through the fuse 39 through the relay coil 38 to the contact 36 through the cross head 49 to the contact 34, to the wire 33 through the junction box 42 to the contact arm 23. When the elevator gates are open approximately fifteen inches or so, the member 16 will be rotated to establish connection between the arms 23 and 22. The circuit continues through the arm 22 to the wire 31 through the junction box 42 to the safety fuse 32 to the negative side of the return line, thus completing the circuit for the first relay switch coil. It will be noted that this circuit is controlled by the switch embodying the contact arms 22 and 23, and that the closing of the gates will open this switch so that the coil 38 is deenergized when the gates are closed.

The circuit to the second relay switch coil beginning with the positive feed wire 49 passes through the safety fuse 39 to the wire 41 through the junction box 42 to one side of the gate switch contact arm 28. When the elevator gates are open approximately 20 inches, the arm 28 will not be electrically connected to the arm 27 but will be while the gates are opened a distance less than the prescribed limits. From the arm 28 the circuit passes to the contact arm 27 through the junction box 42 through the wire 63 to contact 62 on the first gate relay switch, and also to contact 69 on the second relay switch, and also to the reset switch 64 and through this reset switch 64 and the wire 65 to the contact 66 on the first relay switch and through the cross head 48 to the contact 67 to the wire 71 to the contact 70 through the wire 72 to the contact 75 to the wire 76 through the wire 77 to the second relay switch coil 78 through this coil to the wire 85 to contact 86 on the third relay switch and through the cross head 94 to contact 102, which is connected to the contact 103 on the fourth relay switch. From contact 103 the circuit continues through cross head 105 to contact 107 through wire 109 through the safety fuse 32 to the negative side of the return line. It will be noted that the wire 72 connecting to the contact 73 also is connecting to the contact 75 through the resistance 74, this resistance being put in series with the second relay switch coil when the said switch coil has been energized and normally closed. This completes the circuit for the second relay switch coil when the elevator gates are closed, thus closing the second relay switch.

When this circuit is established, the coil 78 will be energized, and immediately upon being energized the cross head 84 will move out of engagement with the contacts 73 and 75 and the cross head 83 will be moved into engagement with

the contacts 69 and 70, thus maintaining a circuit to the coil 78 clear of the reset switch. It will be noted that this circuit through the reset switch necessitates the engagement of the cross head 48 with the contacts 66 and 67.

5

When the gates are open fifteen inches and the first relay switch coil 38 is energized, the arm 48 will be moved out of engagement with the contacts 66 and 67 thus the circuit to the second relay switch coil 78 through the reset switch is broken. However, the cross head 47 will have moved into engagement with the contacts 68 and 62 and thus the circuit will be maintained to the second relay switch coil passing from the wire 41 through the wire 61, contact 60, cross head 47, 15 contact 62, wire 63, wire 68 to contact 69 through cross head 83 to contact 70 through wire 72 to contact 73 through resistance 74 and the wires 76 and 77 to the second relay switch coil 78. This, however, will be effected only when the coil 38 is energized which will be when the gates are open fifteen inches. Consequently it is seen that the resetting of the second relay switch coil 78 cannot be effected while the gates are open, and that the circuit to the second relay switch coil 78 is dependent, when the gates are open, upon the establishing of the circuit through the contact arms 22 and 23. The coil 78 connects through the wire 85 contact 86 cross head 94 contact 102 contact 103 cross head 105 contact 107 to wire 109 and through the safety fuse 32 to the negative return line. The third relay switch coil 91 which is normally deenergized is connected, when the coils 78 and 38 are energized through the wire 90, the contact 89, cross head 30 81, contact 59, wire 58, contact 57, cross head 46 and contact 56 and wire 56' to the armature of the motor, the wire 92 leading from the coil 91 to the opposite side of the armature. This coil 91 is of low voltage, preferably of about 40 24 volts so that is, while the gates are open, that is while the coil 38 is energized, enough current should come onto the elevator armature to make the elevator dangerous to the public, the third relay switch coil 91 will be energized and the 45 plunger or core 93 will move upwardly so that the cross head 94 will disengage from the contacts 102 and 86, thus breaking the circuit to the coil 78 which will drop out the second relay switch and throw out the elevator breaker, at the same 50 time the circuit between the contacts 89 and 59 will be broken, thus breaking the circuit to the armature and cutting out the third relay switch coil which serves to protect from an overloading.

The fourth relay switch coil 54 is connected by 55 the wire 55 to the negative side of the elevator brake coil. The coil 54 is connected by the wire 53 to the contact 50 on the first gate relay switch and when the coil 38 is energized, that is when the gates are open, the coil 54 is connected 60 through the contact 50, cross head 45, contact 51 through the variable resistance 52 to the positive side of the elevator brake coil. Consequently if, when the elevator gates are open, sufficient current should come onto the elevator breaker coil to place the car in danger when the gates are open, the fourth relay switch coil 54 which is of low voltage, preferably 24 volts, will be energized and pull up the plunger 104 so as to disengage the cross head 105 from the contacts 103 and 107 which are connected at one side of the second relay switch coil, thus the circuit to the second relay switch coil 78 will be broken so that this second relay switch coil will drop out 75

and throw out the elevator breaker. When the breaker is out, the circuit to the relay switch 54 will be broken.

It will be noted that the coil 78 is normally energized and that the circuit to this coil 78 is through the contact arms 27 and 28 when the elevator gates are closed, and when the elevator gates are opened the circuit to the coil 78 depends upon the energizing of the coil 38.

10 It is obvious that upon the energizing of either of coils 91 or 54, the circuit between the wires 110 and 112 will be broken as either the cross head 95 will disengage from the contacts 97 and 103, or the cross head 106 will disengage from the contacts 101 and 110. Since the negative side of the circuit breaker coil which is also the negative line of the elevator control switches passes through the circuit between the wires 110 and 112, it is obvious that the energizing of either the coil 91 or the coil 54 will also break the circuit to the circuit breaker coil and break the circuit to the elevator control switches.

25 Should either of the fuses 32 or 39 "blow", the apparatus herein described will automatically shut down the elevator as the circuit established and necessary for the operation of the device passes through either the fuse 32 or the fuse 39.

30 When this apparatus is in use, it would be impossible to move the elevator when the gates are open as the failure of the contacts 17 and 18 to make on the contact arms 22 and 23, will leave the necessary operating circuits broken. Similarly, should any of the traveling cables break or 35 short circuit, or ground, the elevator will automatically shut down.

While I have illustrated and described the preferred form of my invention, I do not wish to limit myself to the precise details of structure 40 shown but desire to avail myself of such modi-

fications and variations as may come within the scope of the appended claims.

Having thus described my invention, what I claim as new and desire to secure by Letters Patent is:

5 1. In electrically operated elevators, having electrically controlled gates and brakes and an operating line for supplying electric current to the operating mechanism and direction switches for controlling the flow of the current through the 10 operating line: a switch normally closed upon the opening of said gate; means operable upon the closing of said switch while any of the direction switches are closed for breaking the circuit to the operating line; and means operable upon the 15 failure of the gate switch to close upon the opening of the gates for breaking the circuit to the operating line.

2. In an electrically operated elevator having electrically controlled gates and brakes, and an 20 operating line for supplying electric current to the operating mechanism: a switch normally closed upon the opening of the elevator gate; and means operable, upon the opening of said gate and the failure of said switch to close, for breaking the 25 circuit to the operating line.

3. In an electrically operated elevator having electrically controlled gates and brakes, direction switches for controlling the flow of current to the operating line, and an operating line for supplying 30 electric current to the operating mechanism: a switch normally closed upon the opening of said gates; means operable upon the closing of said switch while either of said direction switches is closed for breaking the circuit to the operating 35 line; and means operable upon the opening of the gates and the non-closing of said first-mentioned switch for breaking the circuit to the operating line.

PHILIP D. TARDIFF. 40
